TELEVISION CABINET OR SIMILAR ARTICLE

Jack Barofsky, Los Angeles, Calif.

Application November 18, 1953, Serial No. 27,650

Term of patent 14 years

(Cl. D56—4)

FIG. 1.

FIG. 2.

Fig. 1 is a front perspective view of a television cabinet or similar article, with the doors thereof in a partially open position showing my new design;

Fig. 2 is a front elevational view thereof with the doors closed;

Fig. 3 is a rear perspective view thereof with the doors in another open position; and

Fig. 4 is a fragmentary top plan view of Fig. 2.

The dominant features of my design reside in the full line portion of the drawings.

I claim:

The ornamental design for a television cabinet or similar article, as shown and described.
